Primary Examiner — Eric Goodman*Assistant Examiner* — John Reickel(74) *Attorney, Agent, or Firm* — Knobbe Martens Olson & Bear LLP(57) **CLAIM**

The ornamental design for a skin clearing and toning device, as shown and described.

DESCRIPTION

FIG. 1 is a perspective view of a skin clearing and toning device of the present invention;

FIG. 2 is a front elevational view of the skin clearing and toning device shown in FIG. 1;

FIG. 3 is a rear elevational view of the skin clearing and toning device shown in FIG. 1;

FIG. 4 is a left side elevational view of the skin clearing and toning device shown in FIG. 1, the right side view being a mirror image of the illustrated view;

FIG. 5 is a top plan view of the skin clearing and toning device shown in FIG. 1; and,

FIG. 6 is a top plan view of the skin clearing and toning device shown in FIG. 1.

The broken lines are included for the purpose of illustrating portions of the article and form no part of the claimed design.

1 Claim, 3 Drawing Sheets(56)
